BROADCAST ANTENNA

Woodrow Darling, Merchantville, N. J., assignor
to Radio Corporation of America, a corporation
of Delaware

Application May 11, 1945, Serial No. 593,152

10 Claims. (Cl. 250—33)

1

The present invention relates to broadcast antennas and, more particularly, to such antennas designed for ultra short wave operation.

An object of the present invention is the provision of a high frequency broadcast antenna requiring a minimum number of feed points from the transmission line to the antenna structure itself.

A further object of the present invention is the provision of a high frequency antenna which does not require a number of "bazookas" or high impedance trap circuits along the transmission line to prevent the flow of high frequency energy along the outside of the transmission line.

A further object of the present invention is the provision of a high frequency broadcast antenna having substantially a uniform horizontal radiation pattern.

Still a further object of the present invention is the provision of a high frequency broadcast antenna radiating horizontally polarized energy.

Still another object of the present invention is the provision of a multilayer high frequency broadcast antenna having a high gain per layer.

Still a further object of the present invention is the provision of a wide band high frequency broadcast antenna.

Still another object of the present invention is the provision of a high frequency broadcast antenna which is characterized by simplicity of mechanical construction and which is furthermore electrically grounded for protection from lightning strokes.

An additional object of the present invention is to provide an antenna having a minimum number of feed points and uniform horizontal pattern of horizontally polarized radiation and wherein a circular current flow in horizontal planes in the antenna is obtained.

The foregoing objects and others which may appear from the following detailed description are attained by providing an antenna in the form of a vertically disposed hollow conductive cylinder having a circumference equal to a half wavelength at the operating frequency and an overall length, in a preferred elemental embodiment, equal to one wavelength. A narrow longitudinal slot closed at each end is provided along the length of the cylinder. It has been found that by appropriately adjusting the width of the longitudinal slot and the length of the slot, a band width of up to 12 or 15 percent of the midband frequency may be satisfactorily obtained.

Also in a preferred form of the invention a transmission line for connecting the antenna to

the associated transmitting and/or receiving equipment is coupled across the slot at a position midway between its ends.

The structure as so far described may be stacked in a number of vertical layers in order to increase the vertical directivity to any desired extent.

The present invention will be more fully understood by reference to the following detailed description which is accompanied by a drawing in which:

Figure 1 illustrates in elevation an embodiment of the present invention;

Figure 2 illustrates in horizontal cross section a view of the antenna of Figure 1 taken at line 2, 2 of Figure 1;

Figure 3 illustrates in vertical section a modification of the present invention utilizing a pair of vertically stacked antennas such as those shown in Figure 1 to increase the vertical directivity;

Figure 4 illustrates in vertical section a further modification of the present invention utilizing a vertically stacked array of three antennas similar to that shown in Figure 1.

Figure 5 illustrates in vertical section a modified form of the invention shown in Figure 3 wherein a different manner of connecting the feed line is utilized.

Referring now to Figures 1 and 2, there is shown a broadcast antenna in the form of a vertically disposed hollow conductive cylinder 10, having a longitudinal slot 12 extending from one end to the other. The edges of slot 12 may be turned inwardly to form flanges 13 and 14, though outwardly extending flanges may be used if desired. These flanges provide additional structural rigidity and somewhat simplify the problem of making connections from the transmission line to the antenna itself. The slot 12 is preferably electrically closed at each end. A simple way of closing the slot 12 is shown in Figures 1 and 2 wherein short pieces of pipe 16, 16, one at each end of the slot, rest between flanges 13, 14. Bolts 17 pass through holes in flanges 13, 14 and through pipe section 16, 16 rigidly clamping the flanges 13 and 14 against the ends of pipe sections 16, 16.

The antenna is connected to a transmitter or receiver by means of transmission line TL having an outer sheath 18 and inner conductor 20 coaxially arranged within the sheath 18. The transmission line TL passes along flange 14 within the hollow cylinder 10 from the bottom end thereof to midway of slot 12. Here the outer

sheath 18 is terminated and electrically connected to flange 14. The inner conductor 20 then passes across slot 12 and is electrically and mechanically secured to flange 13 by bolting or soldering it thereto. Thus, points P₁ and P₂, to which conductors 18 and 20 are connected lie in a single plane normal to the axis of tube 10, insuring substantially pure circumferential excitation of the antenna, and a total absence of longitudinal excitation.

The outer shell 18 is preferably bonded to the interior of the hollow cylinder 10 at several points along its length so that no difference in potential may exist at any point between the sheath 18 and interior of the hollow cylinder 10 at the line along which shell 18 lies. Generally this is immediately adjacent flanges 13, 14. If desired, flanges 13, 14 may be turned outwardly, in which case it may be preferred to run transmission line TL along flange 14 on the exterior surface of tube 10.

As indicated in Figure 2 the hollow conductive cylinder 10 has an exterior circumference substantially equal to one half of a wavelength at the operating frequency. The length of the antenna, that is, its dimension measured along the slot, is preferably equal to one wavelength at the operating frequency as illustrated in Figure 1. However, this dimension is not critical and may be considerably decreased or increased. In the multielement arrays, to be described later, where a multiplicity of feed points are used, a dimension of three-eighths of a wavelength from each end of each slot to the feed points results in some increase in band width of the antenna.

In an embodiment of the antenna shown in Figures 1 and 2, actually constructed and operated over a frequency range of from 90 to 104 megacycles, the hollow conductive cylinder 10 had a diameter of 18 inches and an overall length of 12 feet. Slot 12 was 3 inches wide while flanges 13, 14 had a width of about an inch and a half. This resulted in a driving point impedance of the order of 40 ohms which could be directly connected to a 50 ohm coaxial line without introducing a serious mismatch between line and antenna. The driving point impedance may be varied to some extent by varying the width of slot 12.

A horizontal field pattern taken indicated that over above-mentioned frequency range there was no more than 6 db variation in field strength in the horizontal plane surrounding the antenna, thus establishing the fact that the antenna is well-suited for broadcasting use.

A similar antenna was also constructed and operated over the frequency range of 80 to 90 megacycles in which the diameter of the cylinder 10 was approximately 24 inches. A 3 inch slot was again used for this modification and, as before, only a comparatively small variation in field strength was detected around the antenna in the horizontal plane.

Figure 3 illustrates a modified form of the invention. Two antennas, each constructed in accordance with Figures 1 and 2, are stacked one above the other, thus making a total overall height of two wavelengths.

The longitudinal slot is divided into two parts 22 and 32, each having a length substantially equal to one wavelength, by intermediate metal spacing bar 16 directly electrically connecting together the midpoints of flanges 13, 14. In order to feed the slots in an in phase relationship the transmission line TL was divided into

two equal length branches TL₁ and TL₂. Transmission line TL₁ crosses and is connected to the upper slot 22 at substantially its midpoint while transmission line TL₂ also crosses and is directly connected to the lower slot 32 at substantially its midpoint. The other ends of transmission lines TL₁ and TL₂ are connected together in a parallel relationship and then connected to transmission line TL. When the transmission lines are thus connected, it is of course desirable that the transmission line TL have a characteristic impedance one-half that of the characteristic impedance of each of transmission lines TL₁ or TL₂ in order that standing waves shall not be set up in transmission line TL. The vertical stacking of two radiators serves substantially to compress the radiation in a narrow angle, thereby increasing the effectiveness of the antenna in all horizontal directions.

Figure 4 illustrates a further modification of the present invention wherein three antennas are stacked vertically in layers one above the other. The hollow cylindrical conductor 40 thus has an overall length of three wavelengths. In this modification the cylinder has three slots 42, 43 and 44 milled or otherwise cut in an end-to-end relationship along one side of the cylinder 40. The slots do not quite meet nor do they come quite to the ends of cylinder 40. Thus conductive bridges 45, 46, 47 and 48 are formed dividing what would otherwise be one continuous slot into three end-to-end slots each having a length substantially equal to one wavelength.

The main transmission line TL in this modification is divided into three branches TL₁, TL₂ and TL₃ connected across slots 42, 43 and 44 hereinafter described. The lengths of transmission lines TL₁, TL₂ and TL₃ must all be equal so that the energy from the transmitter is applied across the slots in an in phase relationship.

Aside from the increased vertical directivity, that is, the compression of the radiated energy into a narrow vertical angle, the operation of the antenna of Figure 4 is the same as the operation of previously described embodiments; that is, currents flow circumferentially over the exterior surface of the system given rise to radiation of horizontally polarized radiation in all directions toward the horizon when the antenna is mounted with its axis vertical, and when transmission line TL is connected to a suitable transmitter.

Figure 5 illustrates a different way of feeding the antenna of Figure 3. Here, the inner conductor 50 of transmission line TL₁ is connected to the left-hand edge of slot 22 and crosses to the right-hand side where it enters the outer sheath 48 of transmission line TL₁. The inner conductor 60 of transmission line TL₂ is connected to the right-hand edge of slot 32 and, crossing slot 32 at the left-hand edge, enters the outer sheath 58 of transmission line TL₂. Thus, these two transmission lines must be fed in a phase opposing relationship. The phase opposing relationship is obtained by connecting lines TL₁ and TL₂ to transmission line TL through a line balance converter 70. The inner conductor 50 of transmission line TL₁ is connected to inner conductor 20 of transmission line TL while the inner conductor 60 of TL₂ is connected to the end of the sheath 18 of transmission line TL. An outer sheath 71 surrounds the end of the sheath 18 of transmission line TL for a distance equal to one-quarter of the operating wave-length and is conductively connected to the outer sheaths 48, 58 of transmission

lines TL_1 and TL_2 . This manner of connecting transmission lines TL_1 and TL_2 to transmission line TL simplifies the problem of obtaining a correct impedance match since now the impedance of transmission line TL must be twice that of the individual transmission lines TL_1 and TL_2 , these individual lines being effectively connected in series.

All of the antenna systems herein described are particularly adapted to broadcast frequency modulated waves such as used for aural broadcasting. Because of the characteristics of the antennas described here, wide frequency deviations may be employed without danger of frequency selective attenuation.

While I have illustrated a particular embodiment of the present invention, it should be clearly understood that it is not limited thereto since many modifications may be made in the several elements employed and in their arrangement which will fall within the spirit and scope of the invention.

What is claimed is:

1. A broadcast antenna including a hollow conductive cylinder having a length substantially equal to one wavelength at the operating frequency and having a circumference of the order of one-half wavelength, there being a narrow longitudinal slot along the length of said cylinder and a coaxial transmission line connected to the edges of said slot at a position half way between the ends of said slot and extending longitudinally along said slot inside of said cylinder and out one end of said cylinder.

2. A broadcast antenna including a hollow conductive cylinder having a length substantially equal to one wavelength at the operating frequency and having a circumference of the order of one-half wavelength, there being a narrow longitudinal slot along the length of said cylinder and a coaxial transmission line extending longitudinally from a position half way between the ends of said slot and along said slot inside of said cylinder and out one end of said cylinder, said coaxial line having an inner conductor extending across said slot and connected to the opposite edge of said slot and said line having an outer sheath connected along the edge of said slot from one end of said antenna to substantially the midpoint of said slot.

3. A broadcast antenna including a hollow conductive cylinder having a circumference substantially equal to one-half wavelength at the operating frequency and a length equal to a multiple of wavelengths, said cylinder having a number of longitudinal slots spaced a multiple of wavelengths including unity apart along the length of said cylinder in an end to end relationship, each of said slots having a length equal to one wavelength and being closed at each end, a coaxial transmission line connected across the midpoint of each of said slots at the edges thereof and means for connecting each of said transmission lines in a parallel relationship to another transmission line which is adapted to connect said antenna to transducer equipment, said first mentioned transmission lines having the same length and each extending longitudinally along the edge of the slot with which it is associated to one end thereof.

4. A broadcast antenna including a hollow conductive cylinder having a circumference substantially equal to a half wavelength of the operating frequency, an overall length equal to two wavelengths, a pair of narrow longitudinal slots ar-

ranged in an end to end relationship along the length of said cylinder, each of said slots having a length lying between three-quarters and one wavelength and being electrically closed at each end, a coaxial transmission line connected across the midpoint to each of said slots at the edges thereof and further means for connecting each of said transmission lines in a parallel relationship to a further transmission line adapted to connect said antenna to transducer equipment, said first mentioned transmission lines having the same length and each extending along an edge of the slot with which it is associated to one end thereof.

5. A broadcast antenna including a hollow conductive cylinder having a circumference substantially equal to a half wavelength of the operating frequency and a length equal to two wavelengths, a pair of narrow longitudinal slots extending along the length of said cylinder in an end to end relationship, each of said slots having a length substantially equal to one wavelength, said slots being closed at each end, coaxial transmission lines each having an outer sheath and an inner conductor connected across the midpoints of each of said slots at the edges thereof, the inner conductor of one of said lines crossing said slots in an opposite direction from the other and means within said cylinder for connecting said transmission lines in a series relationship to the end of another transmission line.

6. A broadcast antenna including a hollow conductive cylinder having a circumference substantially equal to one-half of the operating wavelength and having a narrow longitudinal slot along the length of said cylinder, inwardly turned flanges along each edge of said slot, conductive means joining said flanges together at points along said slot spaced substantially one wavelength apart and a coaxial transmission line having inner and sheath conductors connected to the edges of said slot at points intermediate said first mentioned points said coaxial transmission line extending along said slot inside said cylinder in conductive relationship thereto and out one end thereof.

7. A broadcast antenna including a conductive member constituted by a conductive surface element arranged in the form of a substantially closed hollow member having a narrow longitudinal slot along the length thereof, said member having a length substantially equal to one wavelength at the operating frequency and a mean circumferential dimension of the order of one-half wavelength, and a coaxial transmission line connected to the edge of said slot at a position halfway between the ends of said slot and extending longitudinally along said slot inside of said member and out one end thereof.

8. A broadcast antenna including a hollow conductive member in the form of a substantially continuous surface of revolution, said member having a length substantially equal to one wavelength at the operating frequency and having a circumference of the order of one-half wavelength, there being a narrow longitudinal slot along the length of said member and a coaxial transmission line connected to the edge of said slot at a position halfway between the ends of said slot and extending longitudinally along said slot inside of said member and out one end thereof.

9. A broadcast antenna including a hollow conductive cylinder having a length substantially equal to one wavelength at the operating frequency and having a circumference of the order of one-half wavelength, there being a narrow

longitudinal slot along the length of said cylinder, said cylinder having connection means thereon to connect a coaxial transmission line having an inner conductor and an outer sheath extending longitudinally from a position halfway between the ends of said slot and along said slot inside of said cylinder and out one end of said cylinder across said slot, said connection means including means to connect the outer sheath of said coaxial line along one edge of said slot from one end of said antenna to substantially the midpoint of said slot and the inner conductor of said coaxial line to the other edge of said slot across from the end of said outer sheath at substantially the midpoint of said slot.

10. A broadcast antenna including a hollow conductive cylinder having a circumference substantially equal to a half wavelength of the operating frequency and a length equal to two wavelengths, a pair of narrow longitudinal slots extending along the length of said cylinder in an end-to-end relationship, each of said slots having a length substantially equal to one wavelength, said slots being closed at each end, said cylinder having connection means thereon to connect coaxial transmission lines each having an outer

sheath and an inner conductor across the midpoints of each of said slots at the edges thereof with the inner conductor of one of said lines crossing said slots in an opposite direction from the other.
